NEEDLE GUARD ATTACHMENT FOR
SEWING MACHINES

Louis Saull, Brooklyn, N. Y.

Application November 7, 1933, Serial No. 696,943

2 Claims. (CL. 112—261)

This invention relates to new and useful improvements in a needle attachment for sewing machines.

The invention has for an object the construction of a needle guard attachment which is characterized by great visibility so that the needle may be easily seen, and which is capable of easy attachment upon the presser foot.

Still further the invention proposes the arrangement of a needle guard in a manner so as to give maximum protection.

Still further, the invention proposes constructing the needle guard attachment from a sheet, to provide a portion thereof adapted to be clamped down by a thumb screw which attaches the presser foot to the presser bar, to provide a portion extending vertically along the side of the finger of the presser foot, to provide a horizontal continuation extending rearwards near the shank of the presser foot, and to provide a portion vertically along the other side of the presser foot.

Still further the invention particularly proposes providing the portion for clamping down by the thumb screw with an opening through which the thumb screw may pass.

As another object of this invention an arrangement is proposed whereby the needle guard is provided with a portion extending from the horizontal continuation upwards and attached upon a collar slidably arranged and clamped in position on the presser foot rod.

As another object of this invention it is proposed to provide a portion swivelled upon the horizontal continuation of the needle guard in a manner so as to be capable of assuming a position transversely or longitudinally to be secured by the thumb screw which holds the presser foot, or to a collar slidably arranged on the presser bar.

Still further the invention proposes the construction of a guard as mentioned which is simple and durable and which may be manufactured and sold at a reasonable cost.

For further comprehension of the invention, and of the objects and advantages thereof, reference will be had to the following description and accompanying drawing, and to the appended claims in which the various novel features are 50 more particularly set forth.

In the accompanying drawing forming a material part of this disclosure:—

Fig. 1 is a perspective view of the needle guard attachment applied to a sewing machine and 55 constructed according to this invention.

Fig. 2 is a front elevational view of Fig. 1.

Fig. 3 is a rear elevational view of Fig. 1.

Fig. 4 is an end elevational view of Fig. 1.

Fig. 5 is a perspective view of a needle guard constructed according to a modification of this 5 invention.

Fig. 6 is a front elevational view of Fig. 5.

Fig. 7 is a perspective view of another needle guard constructed according to another embodiment of the invention. 10

Fig. 8 is a fragmentary vertical sectional view taken on the line 8—8 of Fig. 7.

Figs. 9 and 10 are perspective views of other forms of needle guards, constructed according 15 to other embodiments of the invention.

The needle guard attachment for sewing machines, according to this invention, comprises a portion 10 for clamping by the thumb screw 11 which attaches the presser foot 12 to the presser bar 13 of a sewing machine having the conventional type of needle 14 for cooperation with the presser foot. Integral and extending from the portion 10 is a portion 15 which extends along the sides of the long fingers 16 of the presser foot. The presser foot has a short finger 17 on the other side. 20

A horizontal continuation 18 from the portion 15 extends rearwards near the shank of the presser foot and connects with a vertical portion 19 extended longitudinally along the short 30 finger 17.

The portion 10 is provided with an opening 20 through which the threaded portion of the screw 11 passes. The horizontal continuation 18 is formed by merely bending material from the portion 15 rearwards. The portion 19 is formed by bending material from the continuation 18 downwards. The front portion 15 is formed with an opening 21 which is merely for the purpose of increasing the visibility of the 40 device. The upper edge of the portion 15 is formed with a curved cutout 22 serving to increase the visibility from the side. The portion 19 is substantially of U-shape as clearly illustrated in Fig. 3, and at the bottom is provided 45 with a projection 23 adapted to engage against the top of the short finger 16. This projection slightly spaces other portions of the portion 19 from the presser foot so as to further increase the visibility of the guard. 50

In Figs. 5 and 6, a modified form of the invention has been disclosed in which the needle guard comprises a rear portion 18, a front portion 19 joined by a continuation 18, and an upwardly extending continuation 24 from one edge 55

of the continuation 18 terminating immediately adjacent a collar 25 slidable upon the presser bar 13. This collar is held in various adjusted positions by the thumb clamping screw 26. A 5 clamping screw 27 serves to attach the continuation 24 to the collar 25. With this arrangement it is possible to remove the presser foot 12 without disturbing the guard. According to the previous arrangement, when the screw 11 is 10 loosened the presser foot may be removed and the guard will maintain its position on the clamping screw but swing since it is no longer clamped in place. The upper end of the presser foot 12 is formed with a conventional grooved 15 portion which slidably engages a portion 29 upon the presser rod 13.

In Figs. 7 and 8, another variation of the invention has been disclosed in which the main portion of the guard is identical to the forms 20 previously described differing only in the portions by which the guard is attached in place. More particularly, this guard comprises the horizontal continuation 18 which is connected with the portion 15 and with the portion 19. 25 The portions 18, 15 and 19 are constructed as to details similar to the corresponding parts previously mentioned and these details are indicated by the same reference numerals. The support portion 30 is formed with a cylindrical head 31 at the bottom engaging a bracket 32 which is attached upon the top side of the continuation 18 forming a swivel connection so that the portion 30 may be swivelled as desired. A thumb clamp screw 33 threadedly engages through the 30 underside of the continuation 18 against the head 31 to clamp the portion 30 in any position of rotation. The portion 30 is formed with offset parts 34 and 35 formed with apertures 36 respectively. With this arrangement the portion 40 30 may be placed so as to be substantially in the same plane with the continuation 18 and then the guard may be attached to a collar similar to the collar 25 upon the presser foot rod 13. To attach the needle guard by the same screw 45 which clamps the presser bar, it is merely necessary to first loosen the screw 33, to turn the portion 30 at right angles, next to clamp the screw 33, in position to hold the portion 30 in its new position, and finally engage the clamping 50 part 35.

In Fig. 9, a vertical support member 24' has

been provided and is soldered, or otherwise secured to the underside of continuation member 18. This support member is placed adjacent the bar of presser foot 12, to keep the guard more solidly in place.

In Fig. 10, the presser bar 12' is secured directly to support member 24' by soldering, welding or any other manner.

While I have illustrated and described the preferred embodiment of my invention it is to be 10 understood that I do not limit myself to the precise construction herein disclosed and the right is reserved to all changes and modifications coming within the scope of the invention as defined in the appended claims.

Having thus described my invention, what I 15 claim as new, and desire to secure by United States Letters Patent is:—

1. A needle attachment for sewing machines, comprising a front portion for extending along 20 the long finger of a presser foot and having a horizontal continuation extending near the shank of the presser foot, and a rear portion from said continuation extending vertically along the short finger of the presser foot, a 25 support portion swivelly mounted on the horizontal continuation and adapted to be clamped upon a support collar or presser rod, means for holding said horizontal continuation fixed in various swivelled positions, and said support portion having offset parts with openings for selective engagement with a clamp screw coacting with said collar or presser rod.

2. A needle attachment for sewing machines, comprising a front portion for extending along 30 the long finger of a presser foot and having a horizontal continuation extending near the shank of the presser foot, and a rear portion from said continuation extending vertically along the short finger of the presser foot, a 35 support portion swivelly mounted on the horizontal continuation and adapted to be clamped upon a support collar or presser rod, means for holding said horizontal continuation fixed in various swivelled positions, comprising a thumb clamp- 40 screw threadedly engaging through the continuation and against a portion of said swivelled connection, and said support portion having offset parts with openings for selective engagement with a clamp screw coacting with said 45 collar or presser rod.

LOUIS SAULL.
